NILS AXEL LAGERHOLM, OF JONKOPING, SWEDEN

MEANS FOR COLLECTING FILLED MATCH BOXES

Application filed January 17, 1930, Serial No. 421,519, and in Sweden February 11, 1929.

The present invention relates to the manufacture of matches and more particularly to means for collecting the match boxes after they have been filled with matches and the drawers have been introduced into the shells. This collecting operation which is effected with a view to further conveying the boxes to the next machine, as, for instance, a box painting machine, is usually carried out so that the boxes after having been discharged from the filling machine are moved in a continuous row one after the other with the matches lying at right angles to the direction of movement and all with their heads directed to the same side. After a predetermined number of boxes have been moved to the collecting device in this way said boxes will be pushed to the side by a piston and turned over on their edge upon a table, frame or the like situated at a lower level so that the boxes will come to stand upon said table, frame or the like in rows and all with their heads facing to the same direction, usually downwards. This method of collecting the matches, however, causes certain difficulties as to the subsequent operations owing to the swelling of the shells at one end thereof as caused by the heads of the matches. In piling the matches with the said ends facing each other, as for painting, spaces will be left free between the individual boxes into which the friction surface mass may run down. In packing boxes arranged in this way the packets do not obtain a regular shape.

This invention has for its object to overcome said difficulties. To this end, the device to collect the rows of boxes is provided with means to turn every second row of boxes so that the heads of each two successive boxes will face to opposite directions.

In the accompanying drawings several embodiments of the invention are illustrated in a diagrammatic manner.

Fig. 1 is a front view and Fig. 2 is a top plan view of a collecting device according to one embodiment.

Figs. 3 to 5 are side elevations of the same collecting device in three different working positions.

Fig. 6 is a perspective view of a collecting device according to a second embodiment of the invention.

Fig. 7 is a side elevation of the same collecting device.

Figs. 8 to 10 are diagrammatic views to illustrate the operation of three further embodiments of the invention.

With reference to Figs. 1 to 5, the numeral 1 indicates a path, upon which the filled and closed boxes are adapted to be moved in a row one after the other in the direction indicated by the arrow *a* in Fig. 2. In this movement the boxes are turned to the same side with the matches lying at right angles to the direction of movement. Provided at a suitable point of the path 1 is a piston 2 which may reciprocate transversally over the path to pass the boxes from the path 1 over on to a turning plate 3 provided on the one side of the path which is pivoted in two levers 4, 5 which are both secured to a shaft 6 extending parallel to the path 1. The lever 4 extends beyond the shaft 6 and its extension is held in engagement with a cam 7 by means of a spring action on the lever 4. Said cam 7 is driven from a main shaft 8 through the intermedium of an endless chain or the like. The piston 2 may also be driven from said main shaft 8 through means, not shown. Keyed to the shaft of the turning plate is a toothed wheel 9 meshing in a non-rotary toothed segment 10. Provided beneath the turning plate is a table 11. Leading from the path 1 to said last mentioned table is an inclined surface 20. Provided immediately above the table 11 is a reciprocating piston 12 movable parallel with the piston 2 which may be also driven from the main shaft 8 and the purpose of which will appear from the description of the operation of the device as hereinafter set forth.

After a row of boxes has reached a position in front of the retracted piston 2 said row in the forward stroke of the piston 2 will be passed over on to the turning plate 3 which is just in the position shown in Fig. 3, that is, on a level with the path 1. After the turning plate 3 has received a row of matches in the described way the levers 4, 5

with the turning plate will be moved to the right in Fig. 3 due to the action of the cam 7. Due to its meshing in the toothed segment 10 the turning plate 3 will now turn in counter clockwise direction, as seen in Fig. 3, and when the turning plate reaches the position shown in Fig. 4 or an adjacent position, the boxes will slide down from the turning plate and come to stand on their edge upon the table 11. Then the piston 12 will operate to push the row of boxes forward close up to the rows of boxes previously collected on the table which are indicated by dotted lines. The turning plate will continue its rotation 15 until reaching the final position, shown in Fig. 5, in which it will be maintained by the circular portion of the cam during a certain part of the continued rotation of the cam. With the turning plate in this position 20 the piston 2 is again moved forwards to feed a further row of boxes to the side, causing it to slide down directly on to the table 11 along the inclined surface 20 without being turned or stopped by the turning plate 3, the 25 piston 12 then pushing this row of boxes up onto the preceding row. After the piston 2 has then gone back again and is ready to feed the next row of boxes to the side, the concave portion of the cam has come into engagement 30 with the extension of the lever 4, allowing its spring to restore the levers 4, 5 with the turning plate to the position shown in Fig. 3. The next row of boxes is, as a result, received by the turning plate and turned. In this 35 way every second row of boxes will come to lie with the heads of the respective matches facing to one direction, as downwards, whereas the matches of the remaining boxes have their heads facing to the opposite direction, 40 as upwards.

In Figs. 6 and 7 a device similar to that above described is shown, yet with the difference that the turning plate 3 with its toothed wheel is mounted in the frame of the machine, whereas the lever 4 controlled by the cam 7 carries a toothed segment 13 the oscillation of which rotates the toothed wheel 9 and thus also the turning plate 3 in such a way as to cause every second row of boxes, as discharged from the path 1, to be received by the plate and turned, while allowing the remaining rows of boxes to turn over directly down upon the table 11. Like references are used as in Fig. 1, so that the figures may be understood without any special description.

The turning device shown in Fig. 8 is shaped as a rotatably mounted cylinder 21 having a through extending space 22 to receive the boxes. Said space will receive 60 every row of boxes, as discharged from the path 1 by means of the piston 2, but will be caused to perform half a revolution for every second row only. It is thus seen that every second row of boxes will pass directly through 65 the space 22 and will slide without turning

along the inclined surface 23 down upon the table 11, whereas the other rows are turned before reaching the table 11.

A similar turning device is shown in Fig. 9 where, likewise, every row of boxes is passed 70 into a through extending opening 24 formed in a rotary cylinder 25. In this case, however, the cylinder is rotated 90° from the normal position shown alternately to the right and to the left, thereby securing positive guiding of the boxes when discharged in vertical position. By means of a vertically reciprocating piston 26 a simultaneous discharge of the boxes may be obtained. In such case, however, the walls of the opening 75 24 should, preferably, be provided with resilient means to retain the boxes in the discharging position.

A turning device of very simple design is shown in Fig. 10. Attached to a freely rotatable shaft 14 are the plates 15 extending radially and axially and forming an angle of 120° with each other. By means of a ratchet wheel 16 and a pawl 17 connected to the piston 2 said plates are turned 60° every 80 time the piston 2 has moved forward to discharge a row of boxes and then returned. In the position shown one of the plates has received the boxes, but, after the return movement of the piston 2 is completed, the 85 turning device will be in the position shown by dotted lines. The row of boxes will in such case be turned down the inclined surface 18 so that it will come to stand on its edge upon the table 11. Upon the next discharging operation said plate together with the inclined surface 18 will constitute a guide channel for the boxes now dropping directly from the path 1 which will, as a result, be directed to the opposite side to that of the 90 boxes of the row next preceding. For the sake of clearness, the design of the mechanism has not been illustrated in detail, as the details may be varied in different ways 95 as will be readily understood by those skilled 100 in the art.

It is to be noted that it is of no importance, as far as the invention is concerned, whether the boxes after they have left the turning device are collected while standing on their edge or lying upon each other. Thus, for instance, in the said last mentioned case they may collect upon a vertical or inclined frame which is lowered a distance corresponding to the height of a box after each receipt 105 of one row of boxes.

What I claim is:

1. In a device for collecting filled match boxes in which the boxes are fed in a continuous string while resting on one of their flat sides, the combination of means to support said string of boxes, means to discharge successive series of boxes from said string and displace them transversely, a table situated at a lower level than said supporting 110

means and positioned so as to receive said series of boxes as parallel rows, and means to turn every second series of boxes when delivered to the table ninety degrees in one direction and the remaining series of boxes ninety degrees in the opposite direction, so that the alternate rows of boxes collected on the table will have the heads of their matches turned to opposite directions.

2. In a device for collecting filled match boxes in which the boxes are fed in a continuous string while resting on one of their flat sides, the combination of means to support said string of boxes, means to discharge successive series of boxes from said string and displace them transversely, a table to receive said displaced series of boxes as parallel rows, said table being situated at a lower level than said supporting means, stationary means to guide the series of boxes when discharged so as to cause them to turn ninety degrees in a given direction before being delivered to the table so that the boxes will rest on the table on one of their edge sides, and a rotatable turning means to receive a series of boxes at a time from said supporting means, turn it ninety degrees in the opposite direction to that in which the boxes are turned when delivered directly from the supporting means to the stationary guiding means and deliver the series of boxes thus turned to said stationary guiding means.

3. In a device for collecting filled match boxes in which the boxes are fed in a continuous string while resting on one of their flat sides, the combination of means to support said string of boxes, means to discharge successive series of boxes from said string and displace them transversely, a table to receive said displaced series of boxes as parallel rows, said table being situated at a lower level than said supporting means, stationary means to guide the series of boxes when discharged so as to cause them to turn ninety degrees in a given direction before being delivered to the table so that the boxes will rest on the table on one of their edge sides, and rotatable turning means to receive a series of boxes at a time from said supporting means,

turn it ninety degrees in the opposite direction to that in which the boxes are turned when delivered directly from the supporting means to the stationary guiding means and deliver the series of boxes thus turned to said stationary guiding means, said rotatable turning means comprising a rotary shaft, a number of plates on said shaft to act in succession to receive series of match boxes, and means to rotate said shaft at an angle corresponding to half the angular distance between the plates for each series of boxes discharged.

4. In a device for collecting filled match boxes in which the boxes are fed in a continuous string while resting on one of their flat

sides, the combination of means to support said string of boxes, means to discharge successive series of boxes from said string and displace them transversely, a table to receive said series of boxes as parallel rows, said table being situated at a lower level than said supporting means, stationary means to guide the series of boxes when discharged so as to cause them to turn in a given direction ninety degrees in order to allow them to be collected on the table while resting on one of their edge sides, a rotatable turning means to receive every series of boxes discharged from said supporting means, and means to cause the turning means to turn every second series of boxes ninety degrees in one direction and then deliver them to the guiding means and turn the remaining series of boxes ninety degrees in the opposite direction and deliver them to the guiding means.

5. In a device for collecting filled match boxes in which the boxes are fed as a continuous string and all arranged with the heads of their matches turned to the same direction, the combination of means to support said string of boxes, a collecting table situated at a lower level than said supporting means, means to discharge successive series of boxes transversely from said supporting means towards said collecting table so as to cause them to collect thereon as parallel rows, and cooperating stationary and rotatable means to turn alternate series of boxes, when discharged, in opposite directions and after turning them deliver them to the collecting table, so that alternate rows of boxes as collected upon said table will have the heads of the matches turned to opposite directions.

6. A device for feeding successive rows of match boxes and turning alternate rows, said device comprising an upper shelf, a lower shelf extending beyond the end of the upper shelf, a stationary guide-way extending from the end of the upper shelf towards the lower shelf, a rotatable member adjacent said guide-way, means for forcing rows of boxes onto the rotatable member, means for rotating said rotatable member partially for reversing the boxes and delivering them to the guide-way, and means for maintaining said rotatable member out of the path of the next succeeding row of boxes forced from the end of the upper shelf so as to allow said rows to engage the guide-way without being reversed, and means cooperating with the rows of boxes deposited on the lower shelf for forcing the same away from positions below the end of the upper shelf.

7. A device for feeding rows of boxes and reversing the ends of alternate rows, said device comprising an upper shelf onto which all of said rows of boxes are fed, means for moving the rows of boxes transversely on the shelf and forcing them from the end there-

of, a lower shelf extending beyond the end of the upper shelf, a stationary guide-way leading from the end of the upper shelf to the lower shelf, a rotatable member adjacent the end of the upper shelf onto which alternate rows of boxes are forced, means for rotating said rotatable member for reversing alternate box rows and delivering the same to the stationary guideway while allowing the succeeding row to be delivered directly to the guide-way to be placed upon the lower shelf without having been reversed.

8. In a device for collecting filled match boxes, in which the boxes are fed in successive rows while resting on one of their flat sides, the combination of means to support said rows of boxes, a collecting table situated at a lower level than said supporting means, stationary means for guiding the rows of boxes to said collecting table, and rotatable means cooperating with said stationary means to turn alternate rows of boxes in an opposite direction to the other rows and after turning them deliver them to the collecting table, so that alternate series of boxes as collected upon said table will have the heads of the matches turned to opposite directions.

9. In a device for collecting filled match boxes in which the boxes are fed in a continuous string while resting on one of their flat sides, the combination of means to support said string of boxes, means to discharge successive series of boxes from said string and displace them transversely, a table to receive said series of boxes as parallel rows, said table being situated at a lower level than said supporting means, stationary means to guide the series of boxes when discharged so as to cause them to be collected on the table while resting on one of their edge sides, a rotatable turning means to receive every series of boxes discharged from said supporting means, and means to cause the turning means to turn every second series of boxes ninety degrees in one direction and then deliver them to the guiding means and turn the remaining series of boxes ninety degrees in the opposite direction and deliver them to the guiding means.

10. A device for feeding rows of boxes and reversing the ends of alternate rows, said device comprising an upper shelf onto which all of said rows of boxes are fed, means for moving the rows of boxes transversely on the shelf and forcing them from the end thereof, a lower shelf extending beyond the end of the upper shelf, a rotatable member journalled adjacent the end of the upper shelf and adapt-

ed to receive one row of boxes at a time therefrom, means for rotating said rotatable member for reversing alternate box rows while allowing the succeeding row to be delivered to the lower shelf without having been reversed. 70

11. In a device for collecting filled match boxes in which the boxes are fed in a continuous string while resting on one of their flat sides, the combination of means to support said string of boxes, means to discharge successive series of boxes from said string and displace them transversely, a table to receive said displaced series of boxes as parallel rows, means for transferring the box rows to said table while turning them ninety degrees so 80 that the boxes will rest on the table on one of their edge sides, a rotatable member journalled adjacent the end of said supporting means and adapted to receive one row of boxes at a time therefrom, and means for rotating said rotatable member for reversing alternate box rows while allowing the succeeding row to be delivered to the transferring means without having been reversed. 85

12. A device for feeding rows of boxes and reversing the ends of alternate rows, said device comprising an upper shelf, transversely on which all of said rows of boxes are fed, a lower shelf extending beyond the end of the upper shelf, a rotatable member adjacent the upper shelf to receive one row of boxes at a time and reverse it, and means for feeding alternate rows of boxes to said turning member while delivering the succeeding row directly to the lower shelf, so that alternate rows of boxes as collected upon said shelf will have the heads of the matches turned to opposite directions. 100

13. A device for feeding rows of boxes and reversing the ends of alternate rows, said device comprising a supporting surface, transversely on which all of said rows of boxes are fed, a collecting table, means for transferring the box rows to said table while turning them ninety degrees so that the boxes will rest on the table on one of their edge sides, a rotatable member adjacent the supporting surface to receive one row of boxes at a time and reverse the same, and means for feeding alternate rows of boxes to said turning member while delivering the succeeding row directly to the transferring means, so that alternate rows of boxes as collected upon the table will have the heads of the matches turned to opposite directions. 110

In testimony whereof I have signed my name.

NILS AXEL LAGERHOLM.
